(57) **CLAIM**

The ornamental design for a beer mug, as shown and described.

DESCRIPTION

FIG. 1 is a perspective view of a beer mug showing a first embodiment of my new design;

FIG. 2 is a perspective view thereof from the bottom of FIG. 1;

FIG. 3 is a side elevation view thereof from the right side of FIG. 1;

FIG. 4 is a side elevational view thereof from the side opposite that shown in FIG. 3;

FIG. 5 is an elevational view thereof from the right side of FIG. 3;

FIG. 6 is an elevational view thereof from the left of FIG. 3;

FIG. 7 is a bottom plan view thereof; and,

FIG. 8 is a top plan view thereof.

FIG. 9 is a perspective view of a beer mug showing a second embodiment of my new design;

FIG. 10 is a perspective view of the second embodiment from the bottom of FIG. 9;

FIG. 11 is a side elevation view of the second embodiment from the right side of FIG. 9;

FIG. 12 is a side elevational view thereof from the side opposite that shown in FIG. 11;

FIG. 13 is an elevational view thereof from the right side of FIG. 11;

FIG. 14 is an elevational view thereof from the left of FIG. 11;

FIG. 15 is a bottom plan view thereof; and,

FIG. 16 is a top plan view thereof.
